UNITED STATES PATENT OFFICE.

ROBERT M. DIXON, OF EAST ORANGE, NEW JERSEY, ASSIGNOR, BY MESNE ASSIGNMENTS, TO STANDARD HEAT AND VENTILATION COMPANY, INC., OF NEW YORK, N. Y., A CORPORATION OF NEW YORK.

HEATING APPLIANCE.

1,115,411.

Specification of Letters Patent. Patented Oct. 27, 1914.

Application filed February 8, 1912. Serial No. 676,168.

To all whom it may concern:

Be it known that I, ROBERT M. DIXON, a citizen of the United States, residing in East Orange, county of Essex, and State of New Jersey, have invented new and useful Improvements in Heating Appliances, of which the following is a description.

My invention pertains to that class of heating appliances wherein it is desired to produce a large radiating surface which will occupy small space, and has for its particular object to provide such an appliance which may be used in connection with high pressure systems to convey a heating medium under high pressure.

In the drawing, Figure I is a partial elevation and partial section of a portion of a heating appliance embodying my invention. Fig. II is an end elevation of the device shown in Fig. I.

In the drawing, 1 represents a section of a tube, which is preferably a heavy wrought iron pipe adapted to withstand higher pressure than the ordinary cast iron webbed radiators, capable also of holding salt brine or other similar fluids when heated and subjected to heavy pressure and also capable of withstanding shock or even bending under pressure without breakage.

2 represents a flange radiating member, preferably of wrought iron, provided with a horizontal or longitudinally extending flange or collar 3, and the vertical or laterally extending radiating flange 4, that is integral with the longitudinally extending flange 3. The radiating flange 4, if desired, may be provided with perforations, as indicated at 5. The bore of the member 2 is preferably such that when red hot, or far above its working temperature, the same may be driven snugly upon the pipe 1 which may be kept cool, or far below its working temperature as by means of a flow of water therethrough, and thus when the collar is allowed to cool and

contract upon the tube, an extremely tight and elastic fit is secured. Therefore, if the pipe first be properly cleaned and the bore of the collar properly cleaned, and the two members shrunk together as above described they are held together throughout their working temperatures in very intimate con-

tact which causes very slight resistance to the conduction of heat to the radiating webs 4 which webs provide a great radiating surface. By assembling a number of the collars upon the tube and driving them together as shown in Fig. I, I thus produce a heating appliance which may serve to convey a fluid under very high pressure and conduct therefrom and radiate heat very rapidly while little space is required to contain the appliance. If desired to increase the surface which will come in contact with lateral air currents, as for example, a current flowing lengthwise of the tube 1, holes 65 5 may be provided in the radiating flanges to allow passage of air through the flanges.

In Figs. I and II it will be noted the radiating flanges are shown as eccentric and alternated in their relation to each other upon the pipe or tube 1.

Due to its arrangement the exterior air can readily contact with the lateral flanges or come in proximity thereto and thus effectively carry away the heat.

From the foregoing, it will be plain that I have produced a simple and effective heating appliance which may be readily constructed out of wrought iron or other suitable strong and elastic material which will withstand greater pressure and greater mechanical strain than a cast material. Also, it will be obvious that the tube or containing member of my appliance can be threaded or otherwise worked more advantageously than in any cast heating appliance.

I do not wish in any way to limit myself to the exact details or construction shown in the accompanying drawing and described in this specification; for it will be plain that departure in the way of detail may be made without departing from the spirit and scope of my invention, which is as set forth in the following claims.

I claim—

1. A heating appliance comprising a wrought-iron tube, and a plurality of collars having eccentric radiating flanges, the collars being arranged on the tube side by side so as to space the flanges apart, and being secured to the tube while the latter is cooled below its working temperature and

the said collars are heated above their working temperature, the eccentric flanges being alternately arranged with respect to each other.

5 2. A heating appliance comprising a tube and a plurality of radiating flanges in place on the exterior of said tube, said radiating

flanges being eccentric in respect to the tube and alternately arranged in respect to each other.

ROBERT M. DIXON.
